United States Patent Office

Des. 210,815
Patented Apr. 23, 1968

210,815

PANTY GIRDLE

Dennis Montague Brigham, Twilfit House Grove Road,
Farlington, Portsmouth, England

Filed May 12, 1967, Ser. No. 7,082

Claims priority, application Great Britain Dec. 12, 1966

Term of patent 3½ years

(Cl. D2—4)

Fig 1.

Fig 2.

Fig. 3.

Fig. 4.

FIG. 1 is a front elevational view of a panty girdle showing my new design, the broken lines indicating stitching;

FIG. 2 is a rear elevational view thereof;

FIG. 3 is a bottom perspective view; and

FIG. 4 is a side elevational view.

I claim:

The ornamental design for a panty girdle, substantially as shown and described.
